HOLDER FOR EGGS AND THE LIKE

Leon Benoit, Chicago, Ill.

Application December 29, 1932, Serial No. 649,281

5 Claims. (Cl. 229—29)

This invention relates to a cellular holder for small articles requiring individual protection, such as eggs and the like. The holder may conveniently take the form of a filler, i. e., a structure made up of intersecting walls defining cells open at the top and bottom. If desired, such a filler may have its adjacent walls which extend in one direction, converged toward the bottom so as to sustain articles introduced into the cells 10 from the top.

The present improvements have to do both with a holder of the general kind mentioned, and with an enclosure therefor, such as a carton, tube, wrapper or the like. Among the objects of my 15 invention are (1) the production of a holder in the general form of a filler which is severable into two or more cellular components each complete in itself; (2) a connection between such a holder and the enclosure therefor by which the 20 one is secured dependably to the other; and (3) the provision in such a holder and enclosure, in combination, of means by which both may be severed in one operation to provide separate components, each consisting of a smaller cellular holder and enclosure which remain associated in 25 a relatively inseparable manner.

It is with these and other objects, as will hereinafter appear, that my invention is concerned. A construction in which my invention may 30 conveniently be embodied is illustrated in the accompanying drawing in the manner following:

Figure 1 is a plan view of a blank furnishing an enclosure for the present holder;

Fig. 2 is a view in perspective of the blank 35 wrapped around a cellular holder to provide an enclosure therefor;

Fig. 3, which is a similar view, shows the holder and enclosure severed transversely to provide two smaller components each complete in itself;

Fig. 4 is a broken detail view in longitudinal section taken on line 4—4 of Fig. 5; and

Fig. 5 is a view in elevation of one end of the holder surrounded by the wrapper-like enclosure exhibited in the remaining figures.

The illustrated holder A may consist of a set of longitudinal walls 6, 7, 8 and 9, either connected integrally, or independently of each other, in combination with a set of transverse or cross walls 10, 11, 12, 13, 14, 15, 16 and 17. These 50 two sets of walls are each slotted to intersect and interengage in a well known manner. Such a holder construction is, in effect, a filler having two adjacent rows of six cells each, all open at the top and bottom. By arranging the longitudinal walls in converging pairs, as shown in my

Patent No. 1,874,162 granted August 30, 1932, the bottom of each cell is sufficiently closed to support in place an egg or other like article which is introduced thereto.

A holder of the kind described may be used either with or without any enclosure, such as a carton, tube, or wrapper. In case an enclosure is to be provided, however, it will be advantageous in certain ways to use a blank B which is scored along lines a, a', b, b' and c, c' to define sections forming a bottom 20, front and rear walls 21, top sections 22 and flaps 23. Such a blank may conveniently be folded or bent along the several scored lines to surround the holder in the manner illustrated in Fig. 2 where I have 10 shown the two flaps 23 tucked alongside of each other within certain vertical slots 24 extending inwardly from the top edges of the several cross walls midway of their ends. A flaring entrance 15 25 is desirably provided for each slot to facilitate 20 insertion of the flaps therein.

In the holder described, twelve cells are provided, and these are arranged in two adjacent rows of six each. This would be referred to as a 2x6. It requires, as a minimum, three longitudinal walls and seven transverse walls—one more wall in each direction than the number of cells in the rows provided. In the construction shown, four longitudinal partitions are used in order to partially close the bottoms of the cells, 30 but, as already indicated, this would not be necessary with the ordinary kind of fillers in which a single intermediate longitudinal wall suffices to separate both rows of cells. Also, in the construction shown, I have added one extra 35 cross wall, making eight altogether, instead of seven which is the usual number. All eight cross walls may be spaced apart equidistantly, in which event the holder would be divided up into fourteen cells. As illustrated, however, the two walls 40 13 and 14 which are nearest the longitudinal center of the holder may be spaced apart but a short distance, leaving between them narrow cells the presence of which would ordinarily be disregarded. In any event, for a 2x6 holder embodying the features of this invention, it is important to provide (1) longitudinal partitions in number not more than two in excess of the cells in the shorter rows, and (2) transverse walls in 45 number exactly two in excess of the cells in each longer row.

A holder so constructed may conveniently be severed into two (or more) smaller components by providing scores or slits across each of the longitudinal partitions in a single plane as shown 50 55

in Fig. 4. Preferably such a line of severability is midway of the length of the holder, between the two central cross walls 13 and 14. If the holder be cut, broken, or torn apart in this plane of weakness, the two separated components will each remain intact. Each will retain its cellular character, although its capacity will be less.

The enclosure provided for such a holder should desirably be connected to the latter so as not to separate therefrom when handling. More than a mere tucking of the flaps 23 into the cross wall slots 24 is desired. For this purpose, I provide along the edges of the flaps 23 a series of notches 30, one opposite each cross wall. In the operation of tucking the flaps in place, these notches will straddle the cross wall at the bottoms of the slots 24, as indicated by dotted lines in Fig. 4. When advanced thus far, the enclosure flaps are not yet in final position. To assure of a normally inseparable connection, the bottom of each notch terminates in a narrow slit 31 which proceeds transversely of the several bend lines *a*, *b*, *c*, etc. By the application of an appreciable force, the tucked flaps may be pushed down sufficiently to move the slits 31 over the body of the cross walls. When so positioned, the parts are in the position shown by full lines in Figs. 4 and 5. The sheet stock of which the wrapper and enclosure is formed, preferably chip board, straw board, or other fibrous material, undergoes compression for the accommodation of the parts in this final stage of locking. The reverse movement of the flaps necessary for access to the holder or for removal of the enclosure therefrom, will require by the application of a force sufficient to disengage the parts so compressively interlocked. It will be found that such a means of connecting the enclosure to the holder is effective to meet all the usual conditions encountered in the use and handling of such articles.

The severance of the present holder into two components may take place with the enclosure attached in place. This is made possible by providing a line of scoring or slits *y* extending across the wrapper blank between the two flap edges thereof to define a line of severance, as indicated best in Fig. 1. This line of severance lies in a plane which is coincident with the plane in which the several severance lines *x* are provided in the longitudinal partitions. This coincidence is assured by the exact centering of the enclosure lengthwise of the holder consequent upon straddling of the notches 31 upon the cross walls when the two flaps are tucked in place. With the holder and enclosure so connected, the entire structure may then be severed either by breaking or cutting in the plane defined by the lines of severance.

With the division of the holder and enclosure into two (or more) smaller components, each part, although of reduced size, remains in a condition the same as before. The 2x3 components so produced from a 2x6 holder, are equipped each with an enclosure, secured in place as firmly as before, and, in consequence, the present article holder, whether maintained intact in its original form, or separated into two (or more) components, and whether used with or without an enclosure, remains the same as before so far as concerns its general cellular struc-

ture, its relation of parts, and the protection afforded by the enclosure.

I claim:

1. In combination, an article holder made up of two sets of intersecting walls defining cells open at the top, means independent of the holder providing an enclosure therefor extending over the tops of the several cells thereof, means forming a line of severance in a single plane through the enclosure and one set of holder walls whereby to define a plane of separation for the enclosure and holder into two cellular components each complete in itself, and means for interlocking each holder component with its associated enclosure so as to align the lines of severance and prevent separation of one from the other when severed on said line through the enclosure. 15

2. In combination, an article holder made up of two sets of intersecting walls defining cells open at the top and bottom, a wrapper independent of the holder providing an enclosure extending over the top and bottom of the several cells, means forming a line of severance in a single plane through the wrapper and one set of holder walls, and means formed along one edge of the wrapper for frictionally supporting and positioning opposite faces of one set of walls whereby to interlock therewith, whereby to prevent relative movement of the holder and wrapper when severed on said line through the wrapper. 20 25

3. A severable holder for eggs and the like comprising a cellular filler means having transverse walls, a container independent of the filler means providing an enclosure extending over the top and bottom of the cells of the filler means, means forming a line of severance transversely of the container, and means formed at one edge of the container and engaging the opposed faces of adjacent transverse walls to position and hold said walls within said container with one wall 30 35 on each side of said line of severance.

4. A severable holder for eggs and the like comprising a filler means having two cellular components, one component having a wall substantially parallel to and adjacent a wall of 45 the other component, a container independent of the filler means providing an enclosure extending over the top and bottom of the cells of the filler means, means forming a line of severance through said container, and means interlocking each cellular component with the container so that the line of severance through the container divides the space between said adjacent walls, whereby to prevent separation of each cellular component from its associated container portion 50 when severing on said line through the container. 55

5. A severable holder for eggs and the like comprising a filler means having transverse walls defining two cellular components of said filler means, an enclosure independent of the filler means extending over the top and bottom of the cells thereof, means forming a line of severance transversely of the enclosure, and tongue means interlocking each cellular component of the filler means with the enclosure to dispose said transverse walls of said filler means one on each side of said line of severance, whereby to prevent separation of each cellular component of the filler means from its associated enclosure portion when severing on said line through the enclosure. 60 65 70
